CURTAIN

Edward Lepow, Philadelphia, Pa., assignor to
Home Curtain Corporation, New York, N. Y., a
corporation of New York

Application December 31, 1943, Serial No. 516,367

2 Claims. (Cl. 160—349)

This invention relates generally to curtains or similar window coverings and more particularly to novel combination curtain and tieback constructions and method of making the same.

Among the objects of the present invention is the provision of a window covering structure composed preferably of a flexible fabric material and in which the tied back appearance of the curtain is predetermined to a certain extent and wherein at least the interengagement of the tieback and the inner edge of the curtain is predetermined.

As is well known in the art, when curtain panels are hung from a rod or other supporting structure adjacent the upper edge of the window or building opening with which they are associated, it is desirable for the purpose of admitting more light, permitting greater vision through the window or for enhancing the decorative effect produced to change the draped effect thereof by retracting the inner edges of the panels toward their outer edges. This is usually done by a so called tieback which is constructed to harmonize with the curtain panel. The tieback which in use takes a U shaped form has the bight portion thereof engaging the inner edge of the curtain panel while the front and rear legs thereof engage the front and rear surfaces respectively of the curtain panel. The terminals of the tieback are secured to the frame of the window or other building opening. The curtain panels are usually hung in pairs and for the best appearance, it is desirable that the bight portions of the tiebacks on each of the panels become located at substantially the same vertical level. This produces a symmetrical appearance which is pleasing and satisfactory. The majority of prefabricated panel curtains are hung by persons of an average skill who encounter difficulty in properly positioning the tiebacks with relation to the curtain panels. Even where no difficulty is encountered, time is consumed in that there is no indication on the panel where the tieback should engage it. Furthermore, even after the tiebacks have more or less frictionally engaged the curtain panels there is a considerable tendency for the parts to shift out of position with relation to each other. This is caused frequently by a change in the stiffness of the fabrics of which the parts are made, owing to changes in temperature and humidity. The interrelationship in position of the tiebacks and the curtain panels may also change when the curtains are handled to peer between them, or when the curtains are blown out of position by the wind.

Depending upon the general size and propor-

tions of the curtain panels there are certain points along the inner edges of the panels where the tieback should embrace the curtain in order to obtain a desired predetermined hung appearance of the curtain and tieback.

It is therefore an object of the present invention to provide means whereby the bight of the tieback will engage the curtain at a predetermined portion thereof not only when the curtains are originally hung, but also when they are rehung after washing or cleaning.

Although the predetermined engagement of the tieback bight and the curtain is beneficial it is desirable however that these parts may be separated during laundering, cleaning and pressing. Such separability not only prevents the relatively easily damaged extensions of the tieback from becoming knotted or torn but also permits the parts to be more properly smoothed or ironed.

It is, therefore, another object of this invention to provide combination curtain panel and tieback structure in which the tieback may be physically removed from the curtain and subsequently reassembled in a predetermined spatial relationship.

In connection with certain curtain constructions, it is desirable that not only the bight or inner curtain edge engaging portion of the tieback be correlated with the curtain panel but also that the legs of the tieback be correlated in position with the outer edge of the curtain panel. It is, therefore, another object herein to provide combination curtain panel and tieback structure wherein the tieback is detachably engageable with the curtain panel at two portions of the curtain panel.

A feature of the construction just described is provided in that the approximate angular positioning of the tiebacks is predetermined and this predetermined position of the angle of the tiebacks may be made positive within close limits by predetermining the total length of the tieback.

The present invention discloses curtain panel and tieback combinational structure wherein economies in the manufacture thereof are obtained by the simplicity of the structure. According to this novel organization of parts and the integration thereof only a very slight addition to the normal curtain manufacturing operation is required in order to produce embodiments of the present invention so that at no substantial increase in cost, the same are made available to a greater number of potential users.

These objects and other incidental ends and advantages will more fully appear in the progress

of this disclosure and be pointed out in the appended claims.

In the drawings, in which similar reference characters designate corresponding parts throughout the several views:

Figure 1 is a front elevational view of a first embodiment of the invention showing a pair of curtain panels as hung and combined with the tiebacks therefor.

Figure 2 is a front elevational view of the right hand panel of Figure 1 as removed from the supporting rod and with the valance and tieback removed.

Figure 3 is an elevational view of a tieback in extended condition.

Figure 4 is a fragmentary front elevational view taken similarly to Figure 2 and showing the tieback inserted in the curtain panel tieback receiving opening with the tieback in U shaped position, but with the curtain panel not retracted.

Figure 5 is an enlarged fragmentary horizontal sectional view, more or less schematic, as seen from the plane 5-5 on Figure 4.

Figure 6 is a front elevational view taken similarly to Figure 1 but showing the left hand panel only of a second embodiment of the invention.

Figure 7 is a front elevational view comparable to Figure 2 showing the curtain panel of Figure 6 with the tieback removed, and in a substantially planar condition.

Figure 8 is an enlarged fragmentary sectional view, more or less schematic, as seen from the plane 8-8 on Figure 6.

Turning now to the first embodiment of the invention illustrated in Figures 1-5 inclusive, the curtain generally indicated by numeral 10 may include a valence 11, a left curtain panel 12, a right curtain panel 13, a left tieback 14, and a right tieback 15.

The curtain panels are preferably substantially identical, and since they are so, and this is also true of the tiebacks, a detailed description of one will suffice for both.

Thus in Figure 2, the panel 13 may be composed of any suitable material, preferably a flexible textile. A tunnel or rod passage 25 for engagement with the rod 26 may be provided adjacent the upper edge 22 in a well known manner. The panel 13 may be composed of a single piece of material or may as shown be formed by the integration of separate panel portions, as the panel body portion 16 and the decorative band portion 17. The decorative band portion 17 may be disposed along one vertical edge of the panel and may continue along the bottom edge of the panel. Such provision of a decorative band portion in a curtain panel and the integration thereof with the panel body portion 16 is well known in the art and as shown for example in Figure 7 may, where desired, be extended around all of the four principal edges of the curtain panel. As shown in Figure 2, the decorative band 17 therefor, may include a vertical portion 18 extending along and bordering the inner edge 19 of the curtain panel and a bottom horizontal portion 20 extending along and bordering the bottom or lower edge 21. The upper or top edge of the panel 13 is indicated by reference character 22 and the outer vertical or side edge is indicated by reference character 23.

Spaced a substantial distance inwardly from the inner side edge 19 and located between the lower edge 21 and the upper edge 22, the curtain panel is provided with a tieback receiving opening 24. This opening 24 is preferably produced

by severing the material of the panel 13 a distance sufficient to allow the penetration therethrough of the tieback 15. The total size of the opening 24, where the tieback 15 is composed of compressible or foldable material, may be of a length less than the effective height or the width of the tieback transversely of the longitudinal axis thereof. Depending upon the nature of the material or fabric of which the panel 13 is composed, the edges of the opening 24 may be reinforced, as desired, and any suitable structure for this purpose may be utilized as for example treating the cut edges with a permanent type sizing, button hole stitching the edges, or taping them. Such reinforcement of raw fabric edges is well known in the art and is for that reason not particularly described in detail.

The location of the tieback receiving opening 24 vertically, that is to say between the edges 22 and 21 is determined largely by the design which it is desired that the tieback panel will form and this in turn is governed by the aesthetic effect it is desired to produce or the portion of the window or other building opening which it is desired to uncover.

The tieback 15 may be of any well known or desired construction and the tieback 15 as illustrated is of the flounced or ruffled type merely by way of example to produce a coordinated effect with the curtain 10. The width or vertical height of the tieback 15 may be varied. If it is of a stiff material, it is desirable that it be no greater in width than the length of the opening 24 from the upper end 27 to the lower end 28 thereof. The tieback 15 is doubled into U shape in use (see Figure 5) and when so arranged includes a bight 29, a front leg 30 and a rear leg 31. By reason of this doubling therefore, the length of the legs 30 or 31 with relation to the distance between the opening 24 and the outer edge 23 of the panel 13 affects the amount of gathering of the panel 13 which will take place when the curtain panel is hung and drawn back by the tieback. Making the tieback longer will result in a lesser gathering and making the tieback shorter will result in a greater gathering. When the tieback 15 is inserted through the opening 24 and positioned as shown in Figures 4 and 5 it is then drawn back in the direction of the edge 23 and secured to any suitable stationary object as for example the window frame or building opening edge (not shown) by a fastening device 32, such as a tack. The more nearly vertical the legs 31 and 30 of the tieback 15 are arranged the greater will be the compression of the portion of the curtain panel constricted thereby.

It may thus be seen that the installation of a curtain panel 13 is a simple and easy matter. The curtain may be supported by penetrating the passage 25 with the rod 26 and hanging the same upon well known brackets 33. The tieback 15 may have been inserted through the opening 24 either prior to the last mentioned operation or at this time and after it is folded into U shape the terminals 34 and 35 of the tieback are drawn over to the edge 23 and secured in any suitable manner and at any desired angle. Since the bight 29 is vertically located by reason of the location of the opening 24 it is clear that the bight will always assume the same vertical position and this position in turn is correlated with the curtain panel. By virtue of the location of the bight, although the exact positioning of the terminals 34 and 35 is not indicated, it is more easily determined by an optical correlation by the user of

the position of said terminals with relation to the position of the opening 24 or the bight 29.

It may be noted at this point, and by a perusal of Figure 1 that the compressive effect of the bight 29 and the legs 30 and 31 is not directly exerted upon the decorative band portion 17 with the result that this portion adjacent the opening 24 is not subject to the usual crushing effect produced by the bight 29 if the same were to engage the edge 19.

The dismantling of the curtain 10 for the purpose of cleaning and/or pressing is a quick and simple matter since apart from the usual operations to remove the tieback 15 it is only necessary to release the fastening device 32 and to pull one of the legs 30 or 31 until the other leg completely passes through the opening 24. After cleaning or pressing the parts may be reassembled in the manner described hereinabove.

It may be noted that in connection with the second embodiment of the invention, a complete frame for the curtain is provided and there is none of the usual bunchiness or crushing of the peripheral ruffle which is relatively even throughout. This effect is of course noted in the first embodiment in those portions of the curtain panel where the ruffle is provided.

Turning now to the second embodiment of the invention illustrated in Figures 6-8 inclusive, it will be seen that the second embodiment differs from the first embodiment principally in three respects. First, the decorative band exists along the top edge 122 in the decorative band portion 136 and along the outer side edge 123 in the decorative band portion 137. Second, a plurality of tieback receiving openings are provided, not only the tieback receiving opening 124 spaced from the inner edge 119, but a secondary tieback receiving opening 138 is provided. Third, the openings 124 and 138 are obtained by interruptions in the row 139 of stitches which serves to integrate the decorative band portion 117 with the body portion 116.

For the purpose of avoiding needless repetition parts corresponding to those of the first embodiment are given the same reference characters with the addition of a prefix "1."

The operation of the second embodiment of the invention is comparable to that of the first embodiment of the invention with the exception that a portion of the front leg 130 adjacent the terminal 134 penetrates the outer tieback receiving opening 138. This construction serves to locate not only the bight 129 vertically with respect to the curtain panel 113, but also the outer portions, that is to say those portions of the tieback adjacent the terminals thereof. This vertical location of the tieback portions adjacent the terminals thereof with respect to the outer edge 123 of the panel 113 is accomplished since the terminals 134 and 135 are placed in juxtaposition by the penetration thereof by the fastening device 132.

It may thus be seen that by virtue of the construction of the second embodiment where the

length of the tie back has been predetermined a substantially predetermined and uniform hung effect will be produced in a plurality of independent draped curtain panels. The practical effect of this construction therefore, is that an unskilled person may buy a plurality of curtains (those intended to be used in pairs being symmetrically constructed so that the tieback receiving orifices spaced from the outer and inner edges thereof are at uniform heights respectively) and by merely inserting the tiebacks through the tieback receiving orifices and securing the terminals of the tiebacks in a well known manner obtain a predetermined hung appearance in all of the individual curtains so that the draping effect thereof is uniform and harmonious.

I wish it to be understood that I do not desire to be limited to the exact details of construction shown and described, for obvious modifications will occur to a person skilled in the art.

I claim:

1. Curtain construction comprising: an independent tieback; an independent curtain panel provided at its top with means for supporting it from a curtain rod and having a vertical outer edge that is adapted to hang straight, said curtain panel including a panel body with an inner edge and a decorative band secured to the inner edge of said panel body; said curtain panel having an elongated free orifice longitudinally arranged parallel and adjacent to the line of interconnection of the inner edge of said panel body and the decorative band; said tieback extending freely through said orifice and engaging said panel body, said tieback being substantially free of engagement with said decorative band, whereby a portion of the curtain panel may be gathered and drawn toward the outer edge thereof by the tieback, the decorative band being relatively free of compression or gathering by the tieback.

2. Curtain construction comprising: an independent tieback; an independent curtain panel having vertical outer and inner edges and provided at its top with means for supporting it from a curtain rod, said curtain panel including a panel body portion and outer and inner decorative band portions; said panel body portion outer edge being adapted to hang straight; said curtain panel having an outer free opening and an inner free opening; said outer and inner openings being disposed inwardly of the outer and inner band portions respectively; said outer and inner openings being vertically disaligned longitudinally of the curtain panel; said tieback freely passing through both of said openings and being thereby adapted to gather the panel body portion lying between said openings, the decorative band portions being relatively free of compression by said tieback, and the angular disposition of the tieback with respect to the curtain panel being determined by the disaligned location of said openings.

EDWARD LEPOW.
